DESIGN FOR A HAMBURGER PATTY FORMING DEVICE

Irie P. Henderson, Burlingame, Calif.

Application February 20, 1947, Serial No. 137,033

Term of patent 7 years

(Cl. D44—1)

To all whom it may concern:

Be it known that I, Irie P. Henderson, a citizen of the United States of America and a resident of Burlingame, California, have invented a new, original, and ornamental Design for a Hamburger Patty Forming Device, of which the following is a specification, reference being had to the accompanying drawing, forming a part thereof.

Figure 1 is a perspective view of a hamburger patty forming device, showing my new design;

Figure 2 is a rear end view of the device;

Figure 3 is a front end view thereof;

Figure 4 is a top plan view of the device, and

Figure 5 is a side elevation of the same.

I claim:

The ornamental design for a hamburger patty forming device, as shown.

IRIE P. HENDERSON.
